UNITED STATES PATENT OFFICE.

JOSEPH MALICKI, OF CHICAGO, ILLINOIS, ASSIGNOR TO TEMPLETON, KENLY & CO., LTD., OF CHICAGO, ILLINOIS, A CORPORATION OF ILLINOIS.

KEY-LOCK FOR BEARING ELEMENTS.

1,109,851.

Specification of Letters Patent.

Patented Sept. 8, 1914.

Application filed November 13, 1913. Serial No. 800,716.

To all whom it may concern:

Be it known that I, JOSEPH MALICKI, a citizen of the United States, residing at Chicago, in the county of Cook and State of Illinois, have invented certain new and useful Improvements in Key-Locks for Bearing Elements, of which the following is a specification.

This invention relates to improvements in bearings, and has reference more particularly to a new and improved construction of key lock for shaft elements employed in plain bearings.

The chief intended application of my invention is in connection with lifting jacks, and more particularly the bearings of the actuating arm or lever in the frame of the jack. In devices of this kind it is customary to provide the bearing of the pintle of the actuating lever with a hardened steel bushing to reduce the wear and increase the longevity of this part of the device. Heretofore considerable difficulty has been experienced in securely locking these bushings in place against both a rotative and endwise movable tendency.

The object of the invention is to provide a bushing lock of increased simplicity and superior efficiency to those heretofore employed for this purpose.

More specifically, the object sought by the invention is to provide a readily applicable and removable key lock which will securely lock the bushing to the bearing against both rotary and endwise movement and which, at the same time, may be readily removed to permit of the repair or renewal of parts.

My invention, as applied to a lifting jack, is illustrated in the accompanying drawing, 40 in which—

Figure 1 is a fragmentary view of the upper portion of a lifting jack, showing the casing in vertical section, and having my improved key lock applied thereto. Fig. 2 is an enlarged front elevation of the casing with the actuating lever and its socket base removed, and showing one side of the bearing in longitudinal section. Fig. 3 is an enlarged side elevational detail of the casing, in cross-section through one side of the bearing. Fig. 4 is a detail perspective elevation of the right-hand bushing. Fig. 5 is a detail perspective elevation of the key lock that operates with the bushing shown in Fig. 4. 55 Fig. 6 is a fragmentary top plan view of the

inner portion of the lever socket member which carries the lever fulcrum pin.

Referring to the drawings, 10 designates the upper portion of the hollow frame of a lifting jack, of the general type shown in Letters Patent No. 961,909 granted to W. B. Templeton June 21, 1910.

11 is the usual ratchet bar slidably mounted in the casing; 12 is the actuating lever, and 13 the metal lever socket member formed with a seat 14 for the upper or lifting pawl 15, and with a cam 16 for forcing the lower or dogging pawl 17 into place on the down stroke of the lever 12. The lever socket 13 is further formed with laterally extending pintles 18 forming the fulcrum of the lever.

On the front portion of the casing 10 are cast a pair of cylindrical bearings 19, into the outer ends of which may be readily driven cup-shaped bushings 20 that receive the pintles 18 of the lever socket member 13. The upper sides of the bearings 19 are cut away at their inner ends to form openings 21, through which the fulcrum pintles 18 can be introduced to correct position within the bearing members 19. Each bushing 20 is formed with a pair of transverse grooves 22 located on opposite sides of an axial plane of the bushing and preferably in endwise opposed relation to each other.

85 Preferably, and as herein shown, these grooves 22 are disposed at an angle to each other; and when the bushing is in place within the bearing 19 the adjacent ends of the grooves 22 register with the opening 21, lying just inwardly of the opposite side walls of said opening, as clearly shown in Fig. 3. The grooves 22 are of a width somewhat less than the width of the opening 21 in the axial direction of the bearing member; and, 90 preferably, there is formed between the adjacent ends of the grooves 22 a radial aperture 23 which serves both as an outer wall and as a means for equally centering the bushing (by means of a suitable tool entered therein) when the bushing has been entered within the bearing 19.

Fig. 5 shows in detail the key lock. This consists of a strip of metal suitably bent to provide a U-shaped head 24, the sides of which are of a width substantially coextensive with the width of the opening 21 in the axial direction of the bearing member, and a pair of somewhat narrower prongs 25 forming integral extensions of the sides of 110

the head 24; said prongs being of a width suitable to snugly engage grooves 22 of the bushing. When the parts, with the exception of the key, have been assembled in the 5 relative positions shown in Figs. 2 and 3, a key, such as that shown in Fig. 5, is then entered through the opening 21, with the free ends of the prongs 25 at the outer ends of the grooves 22. By means of a hammer 10 the key is driven inwardly, and in this operation the prongs 25 are splayed outwardly to a close fit within the grooves 22. The key is driven in until the inner ends of the sides of the head 24 strike the surface of the bushing member, at which time the outer end 15 of the head is substantially flush with the outer surface of the bearing member 19, the head thus substantially fitting and filling the opening 21. By reason of this construction, the key not only securely locks the bushing against either endwise or rotative movement under the oscillating movements of the actuating lever, but the key itself is securely locked, by means of its outwardly 20 splayed prongs, against accidental displacement. Nevertheless, by means of a hammer and cold chisel the key may be readily pried out for purposes of oiling the bearing 25 or replacing the bushing.

30 Although I have described the invention as embodied in a lifting jack, it will be evident to those skilled in the art that it is equally capable of useful application in other devices employing a bushing member normally liable to endwise displacement or rotary movement or both. Hence, I do not limit the invention to the specific application thereof herein shown and described.

I claim—

40 1. The combination with an annular bearing member having an opening formed through its wall, of a shaft element fitted to said bearing member and formed with a pair of oppositely disposed transverse key grooves disposed on opposite sides of an axial plane of said element and at one end registering with said opening inwardly of the opposite side walls of the latter, and a key member having a head por-

tion substantially fitting said opening and a pair of prongs engaging said grooves. 50

2. The combination, with an annular bearing member having an opening formed through its wall, of a bushing fitted to said bearing member and formed with a pair of transverse key grooves disposed on opposite sides of an axial plane of said bushing, said key grooves lying at an angle to each other with their adjacent ends registering with said opening inwardly of the opposite side walls of the latter, and a key member having a head portion substantially fitting said opening and a pair of outwardly splayed prongs engaging said grooves. 55

3. The combination, with an annular bearing member having an opening formed through its wall, of a bushing fitted to said bearing member and formed with a pair of oppositely disposed transverse key grooves lying at an angle to each other with their adjacent ends registering with said opening 60 inwardly of the opposite side walls of the latter, said grooves having a width less than the width of said opening in the axial direction of said bearing member, and a key member having a U-shaped head portion 65 substantially fitting and filling said opening, and a pair of outwardly splayed prongs forming narrowed extensions of the sides of said head portion and engaging said grooves. 7

4. The combination, with an annular bearing member having an opening formed through its wall, of a bushing fitted to said bearing member and formed with a pair of oppositely disposed transverse key grooves at one end registering with said opening inwardly of the opposite side walls of the latter, and further formed with a radial aperture between the adjacent ends of said key grooves, and a key member having a hollow head portion substantially fitting said opening and a pair of prongs engaging said grooves. 80 85 90

JOSEPH MALICKI.
